[57] CLAIM

The ornamental design for an illuminated display, substantially as shown and described.

DESCRIPTION

FIG. 1 is a perspective view of an illuminated display showing my new design;

FIG. 2 is a front elevational view;

FIG. 3 is a side elevational view;

FIG. 4 is a top plan view, the rear and bottom being plain.

My new design for an illuminated display is believed adequately shown in the above-discussed FIGS. 1—4 of the drawings.
